Primary Examiner—Nelson C. Holtje*Assistant Examiner*—Caron D. Veynar*Attorney, Agent, or Firm*—David L. Baker; Rhodes & Ascolillo[57] **CLAIM**

The ornamental design for a multi-purpose garment pin, as shown and described.

DESCRIPTION

FIG. 1. is a front elevational view of a multi-purpose garment pin showing my new design therefor;

FIG. 2 is a top plan view;

FIG. 3 is a rear elevational view;

FIG. 4 is a bottom plan view;

FIG. 5 is a left side elevational view;

FIG. 6 is a right side elevational view; and,

FIG. 7 is a view of the inner face of one of the end caps shown separately to reveal the design features thereof, it being understood that the opposite end cap is the same.
